UNITED STATES PATENT OFFICE.

EDWIN WRIGHT GROESCHEL, OF JERSEY CITY, NEW JERSEY.

BUCKLE.

SPECIFICATION forming part of Letters Patent No. 670,493, dated March 26, 1901.

Application filed September 4, 1900. Serial No. 28,904. (No model.)

To all whom it may concern:

Be it known that I, EDWIN WRIGHT GROESCHEL, a citizen of the United States, residing in Jersey City, in the county of Hudson and State of New Jersey, have invented certain new and useful Improvements in Buckles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to belt-buckles, and it has reference particularly to that class of such devices in which the buckle consists of two members adapted to be suitably secured to the meeting portions of a belt and to be interlocked with each other by virtue of elastic hooked parts on one member engaging the other member in such manner that the members cannot be readily unlocked, except by imparting thereto a folding or buckling movement, whereby said elastic parts are sprung out of engagement. I am aware that it has been heretofore proposed to construct a buckle of this nature so that one member has a part in the shape of an arrow which is adapted to be engaged by a pair of spring or elastic parts projecting from the other member and having hooked ends whose tips turn slightly inwardly in such manner that when said hooked parts are engaging the arrow their said tips engage the shank of the arrow, and thus disengagement can be most readily effected only by folding or buckling the members in the manner already indicated. Instead of employing the arrow-shaped part I propose to, in effect, split the same longitudinally and dispose the sections thus formed in the member having them in appreciably-spaced relation and with barb toward barb and to correspondingly space the elastic parts of the other member, turning the tips of their hooked portions slightly outwardly, so that they will take under the shanks of the said sections. This construction imparts greater rigidity to the connected members, any possibility of either member moving relatively to the other in the plane in which they lie when connected being perfectly avoided.

My invention therefore consists in a belt-buckle constructed substantially as described above.

I have fully illustrated my invention in the accompanying drawings, wherein—

Figure 1 is a plan view of the buckle, the members being connected or interlocked. Fig. 2 shows the members disconnected, and Fig. 3 is a side view of the member having the hooked portions.

In said drawings, *a* designates one member, and *b* the other member, of my improved buckle. Both members are by preference composed of metal. The metal of the member *a* should be elastic.

The member *b* consists of two side bars *c*, which are inturned near one end and there joined by a bar *d*, while at their other ends they are joined by elongated loop portion *e*, the several parts being of course integrally formed. The loop portion *e* affords a space *f*, through which the adjustable folded portion *g* of the belt *h* may be extended, being held by a spur *i*, which extends from the loop portion *e*, and penetrating one of the holes *j* of said belt. Near the bar *d* the side bars *c* are provided on their inner sides with barbs *k*, which have their rear surfaces converging toward each other, while their surfaces *m* provide stops or abutments.

The member *a* consists of a single bar of the metal bent in such form as to produce the straight bar *n*, to which the other end of the belt *h* is adapted to be secured, and two side bars *o*, extending from the ends of said bar *n* and bent first sharply inwardly into proximity to each other, so as to produce a confined space *p* for said end of the belt, and then diverging slightly toward their ends. Each side bar *o* terminates in a hook *q*, said hooks being just about far enough apart so as to snugly fit between the bars *c* of the member *b* when resting between the barbs and the bar *d* of said member. It should be remarked that the recess *r* is formed as between each barb, and the bar *d* is substantially as wide as the thickness of the metal of the member *a*. Each hook *q* has its extreme end or tip turned sharply outwardly—that is to say, the two tips diverge sharply from each other. Thus when the members of the buckle are interlocked said tips take under about the points

of junction between each side bar *c* and the bar *d* of the member *b*.

In interconnecting or interlocking the members the wearer first places the hooked ends 5 of the member *a* in the space *s* of the member *b*, the side bars *c* of which are slightly farther apart here than at their other ends, and then draws the two members in opposite directions, whereby the hooks *q* are caused to 10 wipe over the barbs *i* until they finally rest in the recesses *r*. In this position the combined pull of the belt and action of the diverging tips of the hooks in taking against the under side of the member *b* obviate perfectly 15 any tendency toward accidental separation of the members. In order to separate them, they are folded or buckled, their directly-engaging portions being forced outwardly, whereby the tips will be crowded together, so that the 20 hooks will release themselves.

By constructing the buckle in the manner described the members are not only prevented from being accidentally turned on each other in their common plane, and thus, possibly, unintentionally disconnected, but a device 25 of substantial and pleasing appearance is produced.

Having thus fully described my invention, what I claim, and desire to secure by Letters 30 Patent, is—

In a buckle, the combination of two mem-

bers, one of said members comprising, integrally formed, a substantially straight intermediate-bar portion, elastic side-bar portions extending from the ends of said intermediate-bar portion and bent first inwardly toward each other, to thus form with said intermediate-bar portion a confined belt-space, and then divergently and having their free ends turned off out of the general plane of said member, thus forming hooks, and the tips of said hooks being bent outwardly away from each other, and the other of said members comprising, also integrally formed, side-bar portions, an intermediate-bar portion 35 adapted to be engaged by the hooks of the other member and connecting said side-bar portions at one end, and an elongated belt-receiving loop portion connecting said side-bar portions at the other end, said last-named 40 side-bar portions converging away from the loop portion and having inwardly-projecting stops or abutments disposed contiguous thereto, substantially as described.

In testimony that I claim the foregoing I 45 have hereunto set my hand this 27th day of August, 1900.

EDWIN WRIGHT GROESCHEL.
